UNITED STATES PATENT OFFICE.

CHARLES AMOS EVANS, OF HAVERHILL, MASSACHUSETTS.

TACK-PULLER.

SPECIFICATION forming part of Letters Patent No. 665,079, dated January 1, 1901.

Application filed September 14, 1900. Serial No. 29,989. (No model.)

To all whom it may concern:

Be it known that I, CHARLES AMOS EVANS, a citizen of the United States, and a resident of Haverhill, in the county of Essex and State of Massachusetts, have invented a new and Improved Tack-Puller, of which the following is a full, clear, and exact description.

The object of the invention is to provide a new and improved tack-puller arranged to permit adjustment for pulling any kind or size of tack and to allow convenient and easy manipulation of the tool on the part of the operator to securely grip the tack and draw the same out of position without much exertion on the part of the operator.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a perspective view of the improvement. Fig. 2 is an inverted plan view of the same with the gripping-jaws in an open position. Fig. 3 is a similar view of the same with the jaws closed, and Fig. 4 is an enlarged side elevation of the improvement.

30 From the end of the handle A projects a fork having spring-arms B B', carrying a pivot-bolt C, on which are mounted to swing jaws D D', extending between the arms B B', as is plainly illustrated in the drawings. The jaws D D' are made of spring metal and are normally open, the arms B B' limiting the opening movement of the jaws and the bolt C limiting the opening movement of the spring-arms 35 B B', so that by adjusting the nut on the bolt C the opening movement of the jaws D D' can be readily limited, according to the size and shape of the tack to be pulled. Thus for a large tack the nut on the bolt C is screwed 40 outward to allow the fork-arms and the jaws to open, and for a small tack the nut is screwed inward to limit the opening movement of the jaws D D' correspondingly. The jaws D D' are formed with inwardly-extending teeth D² 45 for firmly gripping the tack at the shank portion thereof, as is plainly indicated in Fig. 1,

and the said jaws are also provided at their front with outwardly-extending flanges D³ and with a rearwardly-extending foot D⁴, having side flanges D⁵, adapted to rest on the floor 55 or other support when it is desired to close the jaws D D' and to pull the tack by swinging the handle A rearwardly, so that the jaws swing on the foot D⁴ as a fulcrum.

The jaws D and D' are preferably made of 60 two pieces of spring metal fastened together at the foot by a rivet D⁶, so that the upper edges of the two pieces lie close together, while the lower portion is open, as indicated in Figs. 2 and 3. On the foot D⁴ is also formed a projection D⁷, adapted to limit the swinging 65 movement of the jaws relatively to the fork by said projection D⁷ abutting against the shank of the fork at the time the jaws D D' are closed or moved into a gripping position 70 relatively to the tack to be pulled.

On the front of the jaws D D' are formed or secured outwardly-extending inclines E, arranged to travel along fixed parts of the arms B B', so that when a swinging movement is given to the jaws. Then the inclines 75 E by traveling on the fixed portions of the arms B B' cause a closing of the jaws, so that the teeth D² firmly engage the shank of the tack preparatory to pulling the tack out of 80 position.

In using the device the operator places the teeth D² over the head of a tack, so that the teeth stand on opposite sides of the shank of the tack, and then the operator bears down 85 on the handle A, so that the flanges D⁵ of the foot D⁴ rest on the floor, and by now bearing down further on the handle the inclines E traveling on the fixed portions of the fork-arms B B' cause a closing of the jaws, whereby 90 the teeth D² firmly grip the shank of the tack, and by the operator now further bearing down on the handle A the tool swings on the foot D⁴ as the fulcrum, so that the gripped tack is pulled out of position by the jaws D D'. 95 When this has been done and the operator lifts the tool off the floor, and thereby relieves the jaws of pressure, then the latter by their own resiliency open and in doing so force the inclines up the fixed part to cause the jaws 100 to swing upward back to their former position and at the same time allow the tack to

drop out, and thereby permit of immediately reusing the tool for pulling another tack in the manner above described.

Having thus fully described my invention, 5 I claim as new and desire to secure by Letters Patent—

1. A tack - puller, comprising a handle, spring-jaws pivoted to the handle, and means for closing the jaws when pressure is applied 10 to the handle, as set forth.
2. A tack-puller, comprising a handled fork having spring-arms, and a pair of spring-jaws fulcrumed between the arms and normally open, the spring-jaws being arranged to close 15 by applying pressure and to open automatically upon removing the pressure, as set forth.
3. A tack-puller, comprising a handled fork having spring-arms, and a pair of spring-jaws fulcrumed between the arms and normally 20 open, the spring-jaws being arranged to close by applying pressure and to open automatically upon removing the pressure, the jaws having inclines engaging said spring fork-arms, to close the jaws upon imparting a 25 swinging movement to the same, as set forth.
4. A tack-puller, comprising a handled fork having spring-arms, a pivot-bolt carried by said arms and arranged to adjust the spring-arms, and spring - jaws held between the 30 spring - arms and limited in their opening movement by the position of the spring-arms, as set forth.
5. A tack-puller, comprising a handled fork

having spring-arms, a pivot-bolt carried by said arms and arranged to adjust the spring- 35 arms, and spring - jaws held between the spring - arms and limited in their opening movement by the position of the spring-arms, said spring-jaws having inclines arranged to travel on fixed portions of said spring-arms, 40 as set forth.

6. A tack-puller, comprising a handled fork having spring-arms, a pivot-bolt carried by said spring-arms and arranged to open and close said arms more or less, spring-jaws held 45 between the spring - arms and mounted to swing on said bolt, and a foot on said spring-jaws and adapted to rest on a support when using the device, to form a fulcrum for swinging the tool and drawing the tack out of position after it is gripped by said jaws, as set forth.

7. A tack-puller, comprising a handle having a forked lower end, jaws pivoted between the members of the fork of the handle and 55 provided with a rearwardly-extending foot, and means for closing the jaws when pressure is applied to the handle, as set forth.

In testimony whereof I have signed my name to this specification in the presence of 60 two subscribing witnesses.

CHARLES AMOS EVANS.
